TREASURE HUNT GAME BOARD
AND CLUES

Ralph B. Cooney, New York, N. Y.

Application September 12, 1950, Serial No. 184,434

1 Claim. (Cl. 273—153)

1

This invention relates to amusement devices and has special reference to a game played with a board provided with concealed instructions.

The object of the invention is to provide a game which has some of the characteristics and the interest and excitement of a treasure hunt. The game has a special appeal for children, but many older people will also find it amusing and interesting.

A better understanding of the invention and its outstanding characteristics will become more apparent after a perusal of the following description, taken in connection with the accompanying drawings, in which Fig. 1 is a plan view of the front face of a board constructed in accordance with the invention; Fig. 2 is a sectional view taken along the line 2—2 of Fig. 1; Fig. 3 is a fragmentary view of a portion of the board with the facing sheet removed; Fig. 4 is a plan view of the front face of the envelope; Fig. 5 is a plan view of the first clue to one of the hidden compartments provided in the board; Fig. 6 illustrates the type of implement which may be employed in playing the game and Fig. 7 is a plan view of a folded clue contained in one of the hidden compartments.

The board of this invention is composed of a backing 10 upon which is superimposed an intermediate section or layer 11 and a facing sheet 12. The backing 10 and the intermediate section 11 are made of relatively stiff cardboard or other like material. The intermediate section 11 is substantially thicker than the backing 10 to which it is adhered in any suitable manner, as by glue, and such section is provided with a number of apertures which, together with the portions of the backing 10 underlying such apertures, form recesses 13 under the facing sheet 12. The number of such recesses 13 is optional and dependent upon how complicated the hunt is to be made. The location of such recesses 13 is also optional and dependent on the ornamentation upon the facing sheet 12 and the complexity of the hunt for which the board has been devised. The facing sheet 12 is frangible and is preferably made of a sheet of paper which has sufficient thickness or opaqueness to conceal the recesses 13 from the view of the player and yet which may be readily ruptured in the areas defined by the recesses 13 by means of a small implement such as a pencil or the toy shovel 15 depicted in Fig. 6 of the drawings. Preferably, the facing sheet 12 is attached to the board by first connecting an edge portion 14 thereof by means of a suitable adhesive to the upper rear edge portion

2

of the backing 10 (note Figs. 2 and 3) and after such adhesive has dried, folding the sheet over the upper edges of the backing 10 and section 11 and then adhering it with the aid of adhesive to the front face of section 11 while placing the sheet under tension. When adhered in this manner to the board, the facing sheet 12 will be stretched tautly over the recesses 13 and will have no telltale depressions hinting at the location of the recesses 13 therebeneath.

The facing sheet 12 is provided with any desirable drawing, picture or other graphic representation. In Fig. 1 of the drawings, the facing sheet 12 is shown provided with a picture of a country scene in which certain features thereof are arranged in registry with the recesses 13. Thus, as shown in Fig. 1 of the drawings, a recess 13 underlies the signpost 16, the bush 17, the haystack 18, the clump of bushes 19, the bush in front of the covered bridge 20, the gate entrance 21, the doorstep of the abandoned house 22, the anchorage of the springboard 23, the corner of the barn 24 and the foot of the tree 25. It will be understood that while in Fig. 1 of the drawings, the aforesaid recesses are indicated in dotted outline for the purpose of explanation, such dotted lines do not appear on the facing sheet and there is no indication whatsoever on such facing sheet as to the exact location of the recesses in relation to the identified areas. In each of such recesses 13 there is provided a folded piece of paper 26 having written material thereon worded to provide a clue as to where another recess underlies a particular feature of the picture. The initial clue is contained in the written matter provided on a sheet 27 enclosed in an envelope or other suitable container 28 attached to the back of the game board (note Figs. 2 and 3). In such envelope 28 there may be provided a toy shovel 15 or other implement enabling the player to break the facing sheet 12 to find the clues.

The physical construction of the board is not particularly vital to the purposes of the invention. A suitable board may be made of cardboard, as above explained, or wood, or molded thermoplastic material, or any other suitable material. The board also may be made in one piece instead of separate layers 10 and 11, as illustrated. The facing sheet 12 may be made of any suitable frangible material and have a rectangular form as indicated in the drawings, or any other configuration suitable to the graphic representation depicted thereon. Obviously the graphic representation on the sheet 12 may be substantially varied with different boards to pro-

vide different problems or to make the game as simple or complicated as desired.

The game is played as follows: The person playing the game removes the clue 27 from the envelope 28 and determines from the information given thereon where the next clue, which is hidden in the board under a particular feature of the drawing, might be found. With the shovel 15 the player then digs into the facing sheet 12 at that feature of the drawing under which he has decided that the next clue lies. If he has correctly estimated the situation, a recess 13 will underlie such feature and will permit the portion of the facing sheet concealing the same to be broken to enable the player 10 to obtain the clue 26 contained in such recess. This clue will give the player a hint as to where the next clue 28 may be found and he proceeds in this manner until he has uncovered all of the recesses and obtained all of the clues, the 20 last paper 26, of course, advising him that he has successfully completed the game.

The facing sheet 12 is preferably only adhered by a portion of its area to the section 11 so that after a game has been completed it can be removed from the board. Furnished with the board are a number of sheets 12 having similar graphic representations thereon so that they can be successively adhered to the board to enable successive players to try their skill in discovering all of the clues. As is shown in Fig. 1 of the drawings, each sheet 12 has a frame 30 provided thereon to enable the player to place a sheet exactly in proper position in the section 11 so that the graphic features thereon referred to in the clues 26 and 27 are in registry with their corresponding recesses or compartments 13. When that position has been determined, the flap 14 of such sheet can be secured to the back of the board, the clues 26 replaced in their proper positions and such facing sheet secured in position on the front face of the board in the manner previously described. To facilitate this operation, each of the clues and the recess into which such clue should be returned, are designated by corresponding numbers, as is indicated by the numeral 1 applied to the clue 26, shown in Fig. 7 of the drawings, and the numeral 1 applied to the inner surface of the recess designated 13' in Fig. 3 of the drawings.

I claim:

A game apparatus adapted to be played with a plurality of connected clues including a starting clue and all of which clues except the starting clue, are concealed in the apparatus, and comprising a playing board having a flat backing of substantial thickness and provided with a plurality of recesses which open on the upper surface of such backing and are arranged in irregular, spaced relation within the area of said board to provide irregularly sized portions of the board between such recesses, a facing sheet superimposed upon said backing so as to conceal said recesses, said facing sheet being constituted of an unbroken frangible material having on its outer surface a graphic representation provided with a plurality of different, distinguishable features of graphic material arranged in irregularly spaced relation within the representation as a whole, such features of graphic material each overlying a recess in said backing, having a configuration different from that of the recess therebeneath and being of such a nature as to give no hint of the exact location of such recess, and a clue contained in each of said recesses and concealed by the overlying graphic feature on said facing sheet, each of said clues being constituted of a sheet of paper and all, but one, having written matter thereon giving a hint to the player as to a particular part of the feature of graphic material overlying another recess and clue, said clues providing a progressive sequence for the consecutive discovery of all of the clues concealed in said recesses beneath predetermined parts of the graphic features on said facing sheet.

RALPH B. COONEY.
